MULTIPLE CLOTHESLINE REEL

Fred F. Prihoda, San Jose, Calif.

Application October 19, 1948, Serial No. 55,307

5 Claims. (Cl. 242—100)

1

This invention relates to a multiple clothes line appliance and has for its chief characteristic the provision where one or more reels of clothes line could be separately unreeled to any point desired and there the line fastened, each reel being independent of the other as to the length of line used and with the structural elements so arranged that any line or all may be easily wound in again.

Another object is to provide a substantial casing designed to accommodate as many reels as desired when constructed, the casing in this disclosure having only three reels and in any case the said casing to be either permanently attached to the wall as a regular fixture, or hung only when wanted, the casing also carries means whereby the line used may be fastened and securely held.

A further object is to provide appliance of this type to be used either indoors or out where facilities are limited so that the line could be reeled in and out of sight when not in use, and to provide a practical household appliance that is simple in operation, comprising but few parts and inexpensive in construction.

The nature of the invention will be better understood when the following detail description is read in connection with the accompanying drawings.

In the drawings:

Fig. 1 is a detail front elevation of my invention with a sectional view showing the relation of the flexible disk springs to the reels.

Fig. 2 is a front view of the reel showing its composition.

Fig. 3 is a side view of the reel.

Fig. 4 is the front and side view of the flexible disk spring.

Fig. 5 is a perspective view of the axle.

Fig. 6 is a side view of the casing showing the arrangement of the ratchet mechanism with the axle.

Fig. 7 is a side view of the casing with the side plate obviated to show the connection of the cord with the reel and also its connection to the case.

Fig. 8 is a rear elevation of my invention with a sectional view at both sides.

Fig. 9 is a perspective view of the casing showing the cord fastening device.

The multiple clothesline reel in the present instance consists of a casing 50 which may be constructed from any suitable material and may also vary in design without departing from the spirit of the invention, the casing being primarily intended to contain a plurality of clothes line 55

reels to fit various needs and to be used either indoors or in the larger models outdoors, the number of the reels to be determined for the different models when the appliance is being constructed.

Referring to Fig. 1 it will be seen that in this disclosure the casing 50 accommodates three reels of clothes line, the reel 16, Fig. 2, being composed of two identical halves, each half, Fig. 3, being stamped out of a single piece of sheet metal and joined together as shown in Fig. 2 and Fig. 3 at 10, each half having a center opening 11 for the reception of the axle 12 on which the reels revolve. Each half of the reel has its drum portion 15 forced out in about 90 degree angle from the outside wall 21, and part of its face inverted toward the outside portion, providing a hub 23 for the purpose of establishing a safer and wider bearing for the center opening 11 of the reel as shown in Fig. 2. Two apertures 25 and 26 formed in each half of the reel and opposing each other are provided for the insertion of the cord, the aperture 26 having a narrow portion cut through the periphery of the drum, this portion being 25 semicircular but assuming a circular form when the two halves are joined and secured together. Through this opening 27 the cord is inserted into the reel, entering first through the opening 31 in the front of the casing 50 and passing 30 through the reel at 26 and 25 and out through the opening 32 of the rear wall 37 of the casing where the end of the cord is provided with a single knot and pulled back, the knot retaining the cord against the inside of the drum 20 of the reel 16 and associating the cord with the reel as shown in Fig. 7.

Each of the side plates 14 and 14' of the casing 50 is provided with a center bearing 9 for the reception of the axle 12, which together with the crank is formed from a single piece of material. The function of the said axle is twofold, first it supports the reels revolving on the axle when the reels are unreeled and the cord connected to the reel is drawn out as shown in Fig. 6, arrow A. In this operation the axle does not rotate, being held securely through the medium of a ratchet wheel 15 keyed to the axle 12, said ratchet wheel having inclined angular teeth between which a pawl 17 tensioned by a spring 18 drops, preventing the outward rotation of the axle. The second function of the axle takes place when the reels drawn out are wound in again.

Keyed to the axle 12 is the already mentioned ratchet wheel 15 and also a set of flexible disk springs 19, embracing each side of the reel as

shown in Fig. 1 and Fig. 8, said disk springs being designed to impart a moderate pressure against the sides of each reel, producing a spring like friction whereby the reel is secured yieldingly rotatable to the axle. By this arrangement any reel could be drawn out revolving on the securely held axle without interfering with the other, or wound in again by the axle 12 through the medium of the crank 13. The axle rotates in the free direction of the inclined teeth of the ratchet wheel 15 as shown in Fig. 6 by the arrow B and by the reason of the association of the axle with the flexible disk springs 19 the latter embracing the reels with moderate pressure, the axle also rotates the reels to be reeled in.

The flexible disk spring 19 is formed from a round thin disk and stamped out so that the two opposing parts 3 are bent outwardly, and the other two opposing parts 2 are bent inwardly as shown in Fig. 4. By this arrangement one flexible disk spring is capable by its reciprocal pressure to function against two reels as shown in Fig. 1 and Fig. 8. The center opening 7 of the flexible disk spring 19 is the same as the center opening of the ratchet wheel 15, and fitting the axle of which a segment 4 is removed as shown in Fig. 5 and by which means the ratchet wheel 15 and the flexible disk spring 19 are keyed to the axle 12. If desired the openings may be hexagonal or square, the shape of the axle to conform with these openings. The center bearing 11 of the reel 16 and the center bearing 9 of the side plate 14 and 14' must be round in any event.

The axle 12, inserted through the bearing 9 of the side plate 14' carries between the said side plate and a cotter pin 5, secured in the hole 5' of the axle 12 a flat washer 8 provided to equalize the distance from the side plates, the other side having the ratchet wheel 15. The cotter pin 5 retains the outside flexible disk spring 19 which is keyed to the axle maintaining its pressure against the outside reel at this end. The second flexible disk spring 19 contacts this outside reel on the inner side and also the center reel, the third flexible disk spring 19 contacts the center reel and the other outside reel, the fourth flexible disk spring 19 contacting the outside portion of the outside reel on the opposite end. The reels when pressed together with the flexible disk springs are held together by the second cotter pin 6 secured in the hole 6' of the axle 12 as shown in Fig. 1 and Fig. 8. By this grouping the flexible disk springs will exert a certain grip on the reels, enabling the reels to rotate alone or with the axle as explained before. From this order of assembling it will be easily understood, that additional reels may be added if desired, providing the length of the axle and the width of the case is in proportion to the additional reels.

The ratchet wheel 15 fitted to the axle 12 is easily engaged by the pawl 17. This pawl is pivotally mounted at 20 to the side plate 14 and has a narrow extension projecting through the said plate as shown in Fig. 6 and Fig. 8 by which the pawl 17 could be lifted and adjusted to the ratchet wheel. The side plate 14 and side plate 14' are pushed into the grooved channels 34 formed on each side of the front part of the case 50 by which manner the side plates are joined with the front part of the case, the said front part having three spaced extensions 35 each at the top and at the bottom to fit the narrow oblong openings of the rear wall 37 and through which the said extensions are pushed bringing the rear wall 75

37 to a juncture with the front part 50 and the side walls 14 and 14'. When these extensions 35 are bent over even with the rear wall 37 as shown in Figs. 6, 7 and 8, the case is completely joined together.

The openings 31 of the case 50 spaced horizontally above each reel and in the path of the cord are for the passage of the cord and also provide a stop for the reel when the reel is wound in. As mentioned before, each reel is connected yieldingly rotatable to the axle and by this arrangement any reel could be reeled out to any length desired, or reeled in with crank 13 of the axle 12 without any interference with the other.

15 The flexible disk springs 19 embracing each side of the reel 16 and forming a moderate pressure against the reel will yield its grip when a stronger resistance is encountered, which is when the cord reeled in is stopped by its eye 70 against the opening 31 of the case 50 and in which case the reel stops also. The flexible disk springs 19 keyed to the axle and embracing this reel will yield its grip and will slide over the sides of the reel and will rotate with the axle when the axle is turned. It will be apparent that the shortest cord out is wound in first and its reel stopped, the next length out is wound in and its reel stopped, and so on. When only one reel is unreeled, that reel will slide over the sides of its 25 flexible disk springs, these being held in place by the secured axle, and when wound in all flexible disk springs will turn with the axle, sliding over the reels that are in, and gripping only the one that is out and movable and turning it until 30 the reel is stopped as explained before.

35 The case 50 is provided with a cord fastening device 60, Fig. 9, located above the openings 31 of the said case and by which the cord drawn out is fastened at this end. This cord fastening device 40 consists of three V shaped members, one for each reel, and elevated in about 30 degrees from its base, each having at the base on each side cut out portions, forming about 45 degrees angle to provide a triple wedge by which the cord is 45 firmly secured by looping the cord over as shown in Fig. 7 and Fig. 9.

The outside end of the cord, as mentioned before, is provided with an eye 70, this eye has a portion cut away on one side to facilitate its 50 hooking operation at this end, the cord could be secured either by the said eye to a hook, or by a noose formed by the cord when the cord is inserted through the cut out portion of the eye 70, to any convenient object.

55 The rear wall 37 of the case 50 is provided at the top and at the bottom with openings 46 for the reception of wood screws, by which the case could be permanently secured in any convenient place or connected to a hook only when wanted.

60 I believe that the foregoing description, together with the accompanying drawings will explain my invention fully, and I desire to have it understood that any changes may be resorted to when desired, as fall within the scope of what 65 is claimed.

I claim:

1. In multiple clothesline reel, a case having side walls provided with center bearings to accommodate an axle supporting a plurality of 70 clothesline reels, the said case when proportionally designed being able to accommodate as many reels as desired, said case having frontal openings spaced horizontally and in line with each reel for the passage of the cord, the front part of the case being semi-cylindrical from the

vertical center line of the side walls, the reels loosely mounted to the said axle and embraced and gripped on each side with a moderate pressure by flexible disk springs keyed to the axle, a pin inserted through the axle maintaining the reels at one end, another pin inserted through the axle at the opposite end locking the reels and the flexible disk springs together whereby the reels are connected yieldingly rotatably to the axle, means whereby the cord drawn out is fastened to the case, means whereby the outgoing end is fastened at the opposite end, and a crank connected to the axle to wind the reels drawn out in again.

2. In multiple clothesline reel, a case having side walls provided with center bearings to accommodate an axle supporting a plurality of clothesline reels operating within the said case, the reels loosely mounted to the axle each clasped and gripped on each side by flexible disk springs keyed to the axle, the said flexible disk springs imparting a moderate pressure against the reels securing the reels yieldingly rotatably to the axle enabling each reel to be reeled out separately or with the axle when wound in, means whereby the reels and the flexible disk springs are secured together, a ratchet wheel keyed to the axle, said ratchet wheel being held securely and the axle respectively by a pawl tensioned by a spring when the reels are reeled out but capable of rotating in the free direction of the inclined teeth of the ratchet wheel when the crank of the axle is turned, the flexible disk springs keyed to the axle gripping the reels enabling the axle to wind the movable reels in again.

3. In multiple clothesline reel, a case having side walls provided with center bearings to accommodate an axle supporting a plurality of clothesline reels operating within the said case, flexible disk springs each having two opposite quarters bent outwardly the other opposite quarters bent inwardly whereby one flexible disk spring contacts by its reciprocal pressure two reels when interposed between two reels, said flexible disk springs keyed to the axle impart a moderate pressure against each side of each reel connecting the reels yieldingly rotatably to the axle, means whereby the reels and the flexible disk springs are secured together, a ratchet wheel keyed to the axle and held securely by a pawl enabling the reels to revolve separately when reeled out the reels sliding between the secured flexible disk springs, the flexible disk springs gripping the sides of movable reels when the crank of the axle is turned to wind the reels out in again.

4. In multiple clothesline reel, a case having side walls provided with center bearings to ac-

commodate an axle supporting a plurality of clothesline reels operating within the said case, said case having in the front part thereof openings spaced horizontally and in path of each reel provided for the passage of the cord, said cord having an eye affixed to its end by which the cord is fastened when drawn out, said eye also providing a stop for the cord and its reel respectively when the cord is fully wound in, the 5 said eye terminating the inward movement of the cord stopping the reel enabling other movable reels to roate with the axle until stopped, said reels being connected yieldingly rotatably to the axle by flexible disk springs keyed to the axle, 10 means whereby the reels and the flexible disk springs are secured together, said flexible disk springs embracing each reel with a moderate pressure whereby any reel could be reeled out individually or reeled in by the crank of the axle. 15 5. In multiple clothesline reel, a case having side walls provided with center bearings to accommodate an axle supporting a plurality of clothesline reels operating within the said case, the front top of the said case having a cord fastening device comprising a V shaped member for 20 each reel inclined approximately 30 degrees from its base over which the drawn out cord is looped and securely held at this end and an eye affixed to the end of the cord securing the opposite end, 25 the reels being connected yieldingly rotatably to the axle by flexible disk springs keyed to the axle and embracing each side of each reel with a moderate pressure enabling each reel to rotate separately when reeled out or with the axle and the 30 flexible disk springs respectively when reeled in, means whereby the reels and the flexible disk springs are secured together, a ratchet wheel keyed to the axle and held with the axle by a pawl tensioned by a spring when the reels are 35 reeled out but capable of rotating in the free direction of the inclined teeth of the ratchet wheel when the crank of the axle is turned enabling the axle to wind the movable reels in again.
